UNITED STATES PATENT OFFICE

132,564

DESIGN FOR A SKI MITT

Edward C. Lindfelt, Des Moines, Iowa

Application January 26, 1942, Serial No. 105,429

Term of patent 7 years

To all whom it may concern:

Be it known that I, Edward C. Lindfelt, a citizen of the United States and a resident of Des Moines, in the county of Polk and State of Iowa, have invented a new, original, and ornamental Design for a Ski Mitt, of which the following is a specification, reference being had to the accompanying drawing, forming a part thereof.

I claim:

The ornamental design for a ski mitt, substantially as shown.

EDWARD C. LINDFELT.
